UNITED STATES PATENT OFFICE.

DREW REYNOLDS AND HARRY L. SIMPSON, OF DENVER, COLORADO.

ANTI-GLARE SHIELD FOR AUTOMOBILE LAMPS

Application filed August 23, 1927. Serial No. 214,922.

This invention relates to anti-glare shields for automobile lamps, and the general object of the invention is to provide a shield that will kill the glare of the light on an oncoming car and yet give the driver a bright light to drive by, and to provide an anti-glare shield of this character which is an improvement upon the construction shown in the patent granted to Drew Reynolds on March 20, 1928, Number 1,663,177, by the provision of means preventing the light from the lamp from being discharged against the reflector and thence directed into the eyes of an oncoming driver, and to provide a device which is very simple, very cheap to produce, and which may be readily applied to any automobile head-light lamp.

Our invention is illustrated in the accompanying drawing, wherein:—

20 Figure 1 is a side elevation of a lamp bulb having our shield attached thereto;

Figure 2 is a front elevation of the bulb with the shield attached;

Figure 3 is a perspective view of the shield;

25 Figure 4 is a plan view of the blank from which the shield is made.

Referring to this drawing, it will be seen that our anti-glare shield is formed of one sheet of metal, as illustrated in Figure 4, this blank being formed to provide a relatively wide body portion 10, a narrow neck 11 at the forward end of the body portion, and a circular disk 12. The body portion 10 of the shield has its side edges inclined slightly toward the neck 11. Rearward of the body 10 the shield is formed with a longitudinal prolonged portion 13* and two lateral lugs 13.

The blank is formed so that the body portion 10 is longitudinally curved, the disk 12 being bent at the neck 11 so as to extend down in front of the axial center of the bulb. The lugs 13 are semi-circularly bent so as to embrace the neck of the lamp or the base thereof, the ends of the lugs being outwardly turned, as at 14, affording means whereby the lugs 13 may be pressed tightly against the base por-

tion of the lamp bulb or socket or whereby the lugs may be opened out so as to permit the ready removal of the device. The disk 12 is preferably concavo-convex, as shown, and preferably the portion 10 is formed with a longitudinally extending rib 15 which acts to strengthen the portion 10 and render it more rigid and more retentive of the form to which it has been bent.

55 The portion 10 takes care of the top glare, while the centrally disposed disk 12 takes care of the central glare. The small extension 13* which projects rearward of the lugs 13 is adapted to fit between the bulb and the socket 60 so as to hold it firmly in place.

This device does not heat the bulb like other devices for the same purpose and it permits the light to be thrown the same distance ahead with the device on as when the device is off. 65 It kills the glare of the oncoming car and spreads the light to a 45° angle on each side of the road so that the entire road even beyond the fence posts is given a clear, even light.

While we have illustrated a device which is 70 attached to the bulb, yet this metallic shield can be blown in the bulb if desired.

We claim:—

As an article of manufacture, an anti-glare dimmer for headlights formed from a single 75 sheet of metal and providing a relatively wide, transversely flat longitudinally curved body portion having a longitudinally extending rib, a concavo-convex disk-like portion at the forward end of the body portion connected by a neck thereto and extending substantially at right angles to the body portion, the body portion having a rear extension, the rear end of which is adapted to fit within the socket of a lamp and said extensions having curved 80 confronting lugs adapted to embrace the base of a lamp bulb.

85 In testimony whereof we hereunto affix our signatures.

DREW REYNOLDS.
HARRY L. SIMPSON.
